UNITED STATES PATENT OFFICE.

CHARLES F. BURGESS, OF MADISON, WISCONSIN, ASSIGNOR TO C. F. BURGESS LABORATORIES, OF MADISON, WISCONSIN, A CORPORATION OF WISCONSIN.

ELECTRIC HAND-LAMP.

1,185,978.

Specification of Letters Patent. Patented June 6, 1916.

Application filed May 28, 1915. Serial No. 30,964.

To all whom it may concern:

Be it known that I, CHARLES F. BURGESS, a citizen of the United States, residing in Madison, county of Dane, State of Wisconsin, have invented certain new and useful Improvements in Electric Hand-Lamps; and I do hereby declare the following to be a full, clear, and exact description of the invention, such as will enable others skilled in the art to which it appertains to make and use the same:

The present invention relates to electric hand lamps or pocket flash lights, wherein a dry battery is used for delivering current to a miniature lamp located adjacent to the battery and controlled by means of a contact device conveniently positioned for operation by the thumb of the user.

It is the object of the present invention to effect a more reliable connection between the battery and the lamp, and to provide for easier renewal of the battery and to prevent inadvertent opening of the case in which the battery is housed, and to provide a more effective arrangement of lamp and contact device whereby both are mechanically protected and are easily accessible for renewal or repair.

To accomplish the foregoing objects, and others which will become clear from the following detailed description, I support the battery from the cover or closure of the case, wholly independent of the case, and I arrange the active elements of the device so that they can all be assembled in operative relation before the battery is inserted into the case, and before the case is closed by means of its cover. Unlike the common types of hand lamps, the battery does not press against the case and so does not tend to unseat the cover, and, furthermore, by the type of construction here disclosed, the user can see whether he has properly fitted his battery to the lamp, and can examine and adjust all of the working parts while they are freely exposed and easily accessible.

In the accompanying drawings, Figure 1 is a longitudinal central section of the battery case and its cover and associated parts; Fig. 2 is a side elevation of the battery installed on the cover ready for insertion into the case; Fig. 3 shows the bottom of the bat-

tery; Fig. 4 illustrates a modification where-in the battery is secured to the cover by a metal strap which extends entirely around the battery; and Fig. 5 is a front elevation of either modification.

In the drawing, the electric hand lamp comprises a case 1 consisting preferably of sheet metal integral throughout. This case is closed at the bottom and open at the top and is provided with a cover or closure consisting of an insulating block 2 offset at 3 to telescope into the open end of the case with a snug fit. Preferably this insulating block is opaque, as when made of hard rubber, fiber composition, or the like, and is provided with a central recess into which is threaded a metal reflector 4 adapted to receive and make electrical contact with the base of a miniature incandescent lamp 5. At the side of this insulating block or cover is a recess 6 to receive and house a sliding contact device, as hereinafter explained.

On the back side of the cover is a bracket 7 in the form of a metal loop held in place by a screw and adapted to receive the long yielding contact terminal 8 of a dry battery 9, holding that terminal in contact with the central terminal 10 of the incandescent lamp, and also serving as means for detachably securing the battery to the cover. The other terminal 11 of the battery fits within the side recess 6, as shown in Fig. 1.

Within the metal case 1 and extending along the side of battery 9 is a metal strap 12, the front end of which lies in recess 6 and forms an outer wall therefor, and is bent inward across the front face of cover 2 and has its end 13 positioned under the edge of reflector 4 and in electrical contact therewith. The front face of cover 2 may be notched to permit this metal strap to lie flush with its front face, as shown in Fig. 1. The other end of this metal strap is bent over to engage the bottom of the battery at 14.

Within recess 6 is a contact device preferably consisting of a U-shaped leaf-spring 15, one arm of which bears against the insulating block and the other arm of which is provided with a post and thumb piece 16 projecting through a slot in strap 12, so that by sliding the spring backward or forward

in the recess, it may be brought into or out of contact with battery terminal 11 to establish connection therefrom through strap 12 to reflector 4, and thence to the outside lamp terminal, completing the connection through the filament to the other battery terminal 8.

The leaf-spring 15 may have its outer end bent up in the form of a finger 17 fitting in a transverse slot in strap 12, and locking the contact device against sliding movement until inward pressure is applied to thumb piece 16 to free the finger from its slot.

With the arrangement above described, the lamp is sunk into the opaque cover and is thereby protected from breakage, and, furthermore, the light does not strike into the user's eyes and produce the glaring effect which is present in many other types of flash lights. The battery is supported entirely from the cover, and unlike the common types of hand lamps, it does not press against the metal casing and thus tend to open it up. There is in addition the decided advantage that the battery can be fitted to the cover and can be adjusted with respect to the lamp and the contact device, while all of the parts are wholly exposed and freely accessible, and after the several parts have been completely assembled, as shown in Fig. 2, the battery can be slipped into its case as shown in Fig. 1.

In most battery hand lamps there is some freedom of movement of the battery, and this makes difficult the establishment of contact when current is to be delivered to the lamp, and also it frequently causes the lamp to be left on during shipment or when being carried in the pocket. By establishing a comparatively rigid connection between the battery and the lamp, an adjustment once made need not be altered until the battery is worn out, and when this occurs it is a simple matter to pull it out of its case and after unhooking strap 12, swing it around out of bracket 7.

In the modification illustrated in Fig. 4, wherein corresponding parts are numbered as in Fig. 1, the metal strap 12' passes entirely across the bottom of the battery and up the other side thereof, and has its bent end 18 fitted into a saw scarf cut into the side of the insulating cover. With this arrangement the battery is held in fixed but detachable relation to the cover without the need for a bracket on the cover. In other respects the arrangement and advantages are as set forth in connection with the modification first described.

I claim:

1. In an electric hand lamp, the combination of a case, a cover therefor, a lamp in said cover, a battery for said lamp, and a metal strap secured to said cover and engaging the bottom of said battery to de-

tachably secure the battery to the cover so that it may be assembled in operative relation to the lamp before the battery is inserted into the case.

2. In an electric hand lamp, the combination of a case, a cover for said case, a lamp in said cover, a battery in said case and a metal strap secured to said cover and encircling said battery to detachably secure it to said cover.

3. In a battery hand lamp, the combination of a case, a cover fitting into the open end thereof, a lamp in said cover, a battery having one terminal contacting with said lamp and a metal strap secured to said cover and engaging the bottom of said battery to detachably secure the battery to the cover so that it may be assembled in operative relation to the lamp before the battery is inserted into the case.

4. In a battery hand lamp, the combination of a case, a cover fitting into the open end thereof, said cover consisting of insulating material and having a recess, a lamp fitting in said recess, a battery in said case, means for detachably supporting said battery from said cover, said means including a metal strap secured to said cover and engaging the bottom of the battery, and means for connecting said strap to one of the terminals of the battery to permit current to flow therefrom to said lamp.

5. In an electric hand lamp, the combination of a metal case, a cover fitting into the open end thereof and consisting of insulating material, said cover having a recess near its center and having a recess at its side, a lamp in said central recess, a battery having one terminal connected to said lamp and the other terminal lying in said side recess, means for supporting said battery from said cover independently of said case, and a contact device in said recess for establishing connection with the other terminal of said battery.

6. In an electric hand lamp, the combination of a sheet metal case closed at the bottom and open at the top, a battery therein, a cover for said case consisting of insulating material having a recess near its center, and having a recess at its side to receive a contact member, a reflector threaded into said central recess, a lamp mounted in said reflector, a battery in said case supported from said cover independent of said case and a sliding contact device in said side recess for establishing connection between said battery and said lamp, substantially as described.

7. In an electric hand lamp, the combination of a case closed at the bottom and open at the top, a battery therein, a cover for said case, said cover consisting of insulating material having a recess near its center, a lamp in said recess, a bracket secured to said cover

to engage a yielding terminal of said battery and hold it against the central terminal of said lamp, and means for establishing electrical connection between the other terminal 5 of the battery and the other terminal of the lamp, substantially as described.

8. In an electric hand lamp, the combination of a case closed at the bottom and open at the top, a cover for said case, said cover 10 consisting of insulating material having a recess, a lamp in said recess, a bracket secured to said cover, a battery having a yielding terminal extending through said bracket and held thereby against the central terminal 15 of said lamp, and a metal strap secured at one end to said cover in electrical connection with said lamp, the other end of said strap engaging the bottom of said battery to detachably secure the battery to the cover 20 so that it may be assembled in operative relation to the lamp before the battery is inserted into the case.

9. In an electric hand lamp, the combination of a case closed at the bottom and open 25 at the top, a battery therein, a cover for said case, said cover consisting of insulating material having a recess near its center to receive a lamp, and having a recess at its side to receive a contact member, a lamp mounted 30 in said central recess, a bracket secured to said cover to engage a yielding terminal of said battery and hold it against the central terminal of said lamp, the other terminal of said battery resting in the recess at the side 35 of said cover, a metal strap having its front end connected with said lamp and its other end engaging the bottom of the battery so that the battery is supported from the cover wholly independent of the case, and a contact 40 device within the side recess of said cover between said strap and the adjacent battery terminal.

10. In an electric hand lamp, the combination of a sheet metal case closed at the bottom and open at the top, a battery therein, a cover for said case fitting snugly therein, said cover consisting of insulating material having a recess near its center to receive a lamp and having a recess at its side to receive a contact member, a reflector in said recess, a lamp mounted in said reflector, a bracket secured to said cover to engage a yielding terminal of said battery and hold it against the central terminal of said lamp, 55 the other terminal of said battery resting in the recess at the side of said cover, a metal strap having its front end connected with said lamp and its other end engaging the bottom of the battery so that the battery is supported from the cover wholly independ- 60

ent of the case and a contact device within said recess of said cover, substantially as described.

11. In an electric hand lamp, the combination of a sheet metal case closed at the bottom and open at the top, a battery therein, a cover for said case offset to fit snugly in the case, said cover consisting of opaque insulating material having a recess near its center to receive a lamp, and having a recess at its side to receive a contact member, a reflector in said central recess, a lamp mounted in said reflector, a bracket secured to said cover to engage a yielding terminal of said battery and hold it against the central terminal of 65 said lamp, the other terminal of said battery resting in the recess at the side of said cover, a metal strap having its front end contacting with said reflector and its other end engaging the bottom of the battery, so that 70 the battery is supported from the cover wholly independent of the case, and a contact device within the side recess of said cover and movable rearwardly into contact with the adjacent battery terminal, substantially 75 as described.

12. In an electric hand lamp, the combination of a sheet metal case closed at the bottom and open at the top, a battery therein, a cover for said case offset to fit snugly in the 90 case, said cover consisting of opaque insulating material having a recess near its center to receive and completely house a lamp, and having a recess at its side to receive a contact member, a reflector threaded into said central recess, a lamp mounted in said reflector, a bracket secured to said cover to engage a yielding terminal of said battery and hold it against the central terminal of said lamp, the other terminal of said battery resting in 95 the recess at the side of said cover, a metal strap having its front end arranged under the reflector and contacting therewith and its other end engaging the bottom of the battery, so that the battery is supported 100 from the cover wholly independent of the case, and a contact device within the side recess of said cover consisting of a U-shaped spring bearing against said strap and movable rearwardly into contact with the adjacent battery terminal, said spring having a 105 thumb piece projecting through said strap and having an upturned end receivable in a slot in said strap to lock said spring in retracted position until inward pressure is applied to said thumb piece, substantially as 110 described.

In testimony whereof I affix my signature.

CHARLES F. BURGESS.
